UNITED STATES PATENT OFFICE.

WILLIAM H. BARKER, OF LAWRENCE, KANSAS.

ELECTRIC-ARC LAMP.

SPECIFICATION forming part of Letters Patent No. 408,948, dated August 13, 1889.

Application filed November 12, 1888. Serial No. 290,590. (No model.)

To all whom it may concern:

Be it known that I, WILLIAM H. BARKER, a citizen of the United States, residing in Lawrence, Douglass county, Kansas, have invented certain Improvements in Electric-Arc Lamps, of which the following is a specification.

My invention consists of certain improvements in the construction of electric-arc lamps; and one of the main objects of my invention is to so construct such lamps that they will automatically cut themselves out of circuit after being in circuit certain fixed lengths of time, which will vary according to different requirements.

Another object of my invention is to so construct the positive-carbon-holding rod that it will be unnecessary for the lamp-trimmer to clean the rod for the purpose of securing good contact, and so that good contact between the movable rod and some fixed portion of the frame may always be insured at a point which is never exposed to the atmosphere.

In the practical establishment of an arc-light system it is desirable that the different lamps should not be left in circuit and the carbons allowed to burn for longer times than may be provided for in the contracts, or for longer times than the light is actually needed by customers. Some customers need their lamps only for a few hours each night, while others require their lamps to be in circuit for longer periods, and in some cases all night. For this reason it has been customary to have separate circuits for lamps which are to be used different lengths of time, all the three-hour lamps, for instance, being on one circuit, while all the six-hour lamps, for instance, are on another circuit, no matter whereabout in the system they may be located.

It is one of the objects of my invention to so construct the lamps that lamps which are to be used for different lengths of time—as, for instance, three, five, six, or eight hours at a time—may be used on the same circuit, if desired, and that each lamp will automatically cut itself out of circuit without leaving any resistance in its place when its positive carbon has burned a certain length, or, what is the same thing, when the lamp has been in use the provided number of hours. For this

purpose I provide the positive-carbon-carrying rod with devices at proper points in its length, and combine therewith a cut-out, 55 which, when the rod has descended a certain distance, will short-circuit the lamp out, as hereinafter described.

My present invention includes certain other improvements, which will be set forth in the 60 course of the following description.

In the drawings I have illustrated my improvements as applied to a lamp provided with the well-known Thomson-Houston regulating devices; but it will be understood that 65 my invention is applicable to various constructions of arc lamps.

In the accompanying drawings, Figure 1 is a vertical section of sufficient of an arc lamp to illustrate my invention. Fig. 2 is a plan 70 view on the line 1, 2, Fig. 1, the sheet-metal casing around the regulating devices being removed. Fig. 3 is a perspective view of the carbon-holding rod drawn to a larger scale. Fig. 4 is a perspective view of a contact-lever 75 H'. Fig. 5 is a perspective view of a modification, and Fig. 6 is a view of a still further modification.

In setting forth the present invention it will not be necessary to describe in detail the 80 construction of the lamp and the regulating devices illustrated, for, as I have already said, they are of well-known construction and do not form any essential part of my invention, and they may be varied as circumstances 85 make desirable. It will suffice, however, to say that in Figs. 1 and 2 of the accompanying drawings A is the frame of the lamp, having an inclosing-case a for the regulating devices, and the upper part of the frame carries the inclosing-tube B for the positive-carbon-carrying rod, while to the lower portion of the frame are secured the arms a', which carry the negative carbon and globe. (Not shown.)

E are the regulating-magnets, with the armature e on the pivoted armature-lever e', and F is the clamp carried by said armature-lever to act on the positive-carbon-carrying rod D in the usual manner for the formation 90 of the arc and the feeding of the carbon. The lower end of this carbon-carrying rod D is provided with a clamp d' for the positive carbon p, while at its upper end it is pro-

vided with a brush *d*, having spring contact-fingers which bear against the inside of the conductor-tube *G*, held centrally within the inclosing-tube *B* of the frame by means of insulating-blocks *b* at its upper and lower ends. This metallic conducting-tube is electrically connected with the positive terminal of the lamp and is highly polished on the inside, so that the contact-brush on the upper part of the carbon-carrying rod may move freely thereon and make continuous contact with the inside of the tube at points which are never exposed to the atmosphere, and consequently the cleaning of the carbon-carrying rod usually required with ordinary lamps becomes unnecessary.

In the circumference of the carbon-carrying rod I form at the desired point or points notches *n*, which may or may not extend all around the circumference of the rod, although I prefer to extend them all the way around.

I provide on the frame of the lamp at suitable point an automatic cut-out consisting of a fixed and pivoted contact to operate in connection with the notches on the rod. The fixed contact is connected to one terminal of the lamp, while the movable contact is electrically connected to the other terminal of the lamp, so that when the contacts meet the short circuit will be closed and the lamp with its regulating-coils cut out of circuit, thus leaving in its place practically no resistance. In the present instance I have shown the fixed contact *H* as electrically connected to the binding-post *P* and provided with a suitable adjusting-screw *h*. The pivoted contact consists of a small bent lever *H'*, having a fine edge to bear against the side of the carbon rod *D* and to enter the notch or notches therein when it or they shall come opposite it. This pivoted contact-lever is acted on by an adjustable push-spring *h'*, which tends to press the edge of the lever against the edge of the carbon-carrying rod and into the notch or notches when one presents itself. This pivoted lever is connected to the binding-post *P* of the lamp.

The contact-lever *H'* is preferably so arranged in reference to a cam *M* or other device, which is used to operate the armature-lever *e'* and its clamp *F*, so as to release the carbon-carrying rod, that when this cam is turned by its insulated handle *m*, or otherwise, to free the clamp *F* a portion of the cam will act on the rear end of the lever *H'* and disengage its edge from the notch in the carbon-carrying rod *D* and allow the latter to feed forward. Then on returning the handle *m* and cam *P* to their normal positions the lamp is thrown into circuit again, and the notch having descended below the lever *H'* the lamp is thrown into operation again for another period of time, or until the next notch comes opposite the movable contact *H'*.

The number of notches in the peripheries of the carbon-carrying rods and their distances apart in each rod will vary of course

with the lengths of time which the different lamps containing these rods are intended to burn. In the drawings I have shown the rod *D* as provided with three of these notches at such distances apart that the lamp will burn, say, three hours at a time, for instance, before it is automatically cut out in the manner above described—that is, by the entry of the pivoted contact *H'* into the approaching notch in the carbon-carrying rod and the consequent closing of the short circuit across from one binding-post *P'* to the other *P*.

The carbon-carrying rod is shown as covered with an insulating-sleeve *S*, so that the cleaning of this carbon-carrying rod becomes unnecessary, and there can be no contacts or short circuits by the bearing of the pivoted contact-lever *H'* upon the rod. It should be understood, however, that, if preferred, the bearing-face of the contact-lever *H'* may be provided with insulating material in place of that now upon the carbon-carrying rod itself. I prefer, however, to provide the contact-carrying rod *D* with the insulating-sleeve, although, if desired or preferred, another metal cylinder may be slipped over the insulating-sleeve.

In Figs. 2 and 3 I have shown the notches in the carbon-carrying rod as extending all around its circumference; but this is not necessary, and the notches may be on one side only, so that by turning the notched side toward the pivoted contact *H'* the lamp may be arranged to automatically cut itself out when a certain amount of carbon has been burned, while by turning the rod around, so that the other side is presented to the pivoted contact, the lamp may be arranged to burn until the carbon is exhausted, or, if provided with notches differently spaced, may be arranged to burn for a different number of hours. In Fig. 5 I have indicated the rod as made in a polygonal form with differently-spaced notches on different sides, so that the lamp using such a rod might be arranged to burn for a different number of hours, according to the size of the rod which is turned to the pivoted contact-lever *H'*.

The head-piece carrying the brushes *d* may be swiveled to the carbon-carrying rod, or the lamp *d'* at the lower end may be swiveled to this rod.

When the arc lamp is provided with two sets of carbons, one carbon-carrying rod may be provided with one set of notches, while the other carbon-carrying rod may be provided with notches differently spaced, so that by using one pair of carbons the lamp may be burned for a certain number of hours, while by turning the current through the other pair of carbons the lamp may be in operation for another different number of hours.

I claim as my invention—

1. The combination of the terminals of an electric-arc lamp with a cut-out having contacts one in connection with one terminal and the other with the other terminal, and

the positive-carbon-carrying rod having at intervals, corresponding with the lengths of time the carbon is to burn, means, substantially as described, for closing the cut-out.

5 2. The combination of the terminals of an electric-arc lamp with a cut-out having contacts one in connection with one terminal and the other with the other terminal, and the carbon-carrying rod having at intervals 10 notches into which the movable part of the cut-out can enter to automatically cut out the lamp, substantially as set forth.

3. The combination of the terminals of an electric-arc lamp with a cut-out having contacts one in connection with one terminal and the other with the other terminal, and a carbon-carrying rod having at intervals on 15 one side notches into which the movable part of the cut-out can enter to short-circuit the lamp, substantially as specified.

20 4. The positive-carbon-carrying rod of an arc lamp having an insulating-cover.

5. The combination of the terminals of an electric-arc lamp with a cut-out having contacts and a carbon-carrying rod having an 25 insulating-cover with notches at intervals, into which the movable part of the cut-out can enter to short-circuit the lamp, substantially as specified.

6. The combination of the frame of an arc 30 lamp having a conductor-tube with the movable carbon-carrying rod having a contact-brush at its upper end and having on its main body an insulating-cover.

In testimony whereof I have signed my name 35 to this specification in the presence of two subscribing witnesses.

WILLIAM H. BARKER.
